TIME CONTROLLED ANNUNCIATOR

Peter Henrik Henrikson, Los Angeles, Calif.

Application November 22, 1933, Serial No. 699,271

7 Claims. (Cl. 161—6)

This invention relates to time controlled annunciators, and same has for its principal object to provide an annunciator which may be very easily combined with the essential working parts of an alarm clock and which will include a decidedly novel setting mechanism and means co-operable therewith for causing the alarm to sound either at a single predetermined time or periodically and at different predetermined times as may depend upon the use to which the annunciator is put.

The annunciator is primarily, but not necessarily, designed for use for the purpose of reminding one that a particular time of the day has approached for the tuning of a radio receiver for the reception of a particular program which is to be broadcast from a certain sending station. I am more or less familiar with various well known types of station tuning mechanisms for use in connection with radio receiving instruments and that they have had for their purpose the automatic tuning of the receiver at a predetermined time. Such automatic station selectors or tuners have not proven entirely practical for more than one reason. They are usually complicated; not always entirely reliable and are somewhat costly and difficult of operation. In view thereof, I have designed an instrument whose cost should not much exceed that of an ordinary alarm clock, one which is of light weight and freely portable and which may be used to satisfy all of the ordinary purposes of an alarm clock, thus enabling the instrument to be employed in this highly distinctive dual capacity. I have further constructed the instrument so that use thereof shall not require that it be incorporated in a receiving set or connected with any of the working parts of said set.

A very important object of my invention is directed to a novel alarm setting mechanism whose design makes possible an almost unlimited range of time adjustments, whereby the alarm may be made to sound on the hour; or at fifteen, thirty or forty-five minutes thereafter, or at times separated from each other by fifteen minute intervals between any two consecutive hour indications upon the dial of the instrument.

Other new and novel features of the invention will suggest themselves to those skilled in the art upon reference to the accompanying drawings, in which

Figure 1 is a view in front elevation of the annunciator;

Figure 2 is a view in rear elevation of a portion of the dial showing the alarm releasing means of the hour hand arbor;

Figure 3 is a section taken on the line 3—3 of Figure 2;

Figure 4 is a section on the line 4—4 of Figure 3;

Figure 5 is a view in side elevation of the annunciator, with parts broken away and parts in section;

Figure 6 is a view somewhat like Figure 5, showing the parts in the positions assumed when detent mechanism has been released at a predetermined time;

Figure 7 is a view in elevation of a portion of 10 the casing showing the form of minute dial employed;

Figure 8 is a section on line 8—8 of Figure 5, looking in the direction of the arrow;

Figure 9 is a view in elevation showing the 15 alarm tripping mechanism in its set position;

Figure 10 is a view similar to Figure 9, showing the alarm tripping mechanism in a tripped position as when sounding the alarm;

Figure 11 is a view similar to Figure 10, showing the positions of the parts of the alarm tripping mechanism such as they would occupy just prior to their return to their set positions;

Figure 12 is a view in edge elevation of parts 25 of the clock mechanism and parts of the alarm tripping mechanism;

Figure 13 is a vertical section taken substantially on the line 13—13 of Figure 12;

Figure 14 is a section taken on the line 14—14 of Figure 11.

In Figures 1 and 2 of the drawings is illustrated a clock casing 10, at the front of which is an hour dial 11 through the center of which passes an hour hand arbor 12. The said dial is provided with an outer portion 13 formed with 35 twenty-four radial slots 14. These slots are equi-distantly spaced apart from each other and the alternate ones are alined with the respective hour markings H on said dial, and the others are positioned just midway between the 40 said hour markings. These slots open at their outer ends onto the peripheral edge of said dial and lying in a position parallel to each slot is a friction inducing spring 15. Mounted to slide in each of the slots is an elongated 45 predetermining element 16, the transverse shape of which is circular as shown in Figure 4. These elements are formed at their sides with longitudinal grooves 17 in which the edge walls of the slots 14 are received, whereby the elements 16 can be moved radially of the dial. The springs 15 are threaded through the mating elements 16 and same coact with the adjacent grooves 17 to yieldingly bear against the walls 55 thereof to induce sufficient friction between the elements and the springs to cause said elements to be retained in their selected positions of radial adjustment in the slots 14. Midway of its ends, each of said elements 16 is formed with 60 a kerf or marking 18 and same is adapted to

coincide with a concentrically positioned band or marking 19 on the dial. It will be noted that the elements 16 are of short length with respect to the length of the slots 14 so that they may each be moved to any one of several possible positions on the dial, as will be appreciated upon reference to Figure 1 of the drawings.

In back of the dial 11 and secured in a fixed position on the arbor 12 is a large pinion 20 which meshes with a small driven pinion 21, the latter constituting a part of a clock mechanism to be described later. The pinion 20 is accommodated in the slot 22 in a plate or head 23, the latter flanged at 24 within the annular walls of the casing 10 as shown in Figures 5 and 6. The arbor carries a fixed radial arm 25 of resilient material, at one side of which is a power transferring member 26, the same hinged at 27 to said arm 25 so that it can move laterally with respect to the inner face of the dial 11. The hour hand arbor is formed with an axial bore 28 in which a pin 29 is mounted for limited sliding movement. Positioned in back of the pin is the angular branch 30 of an oscillating shaft 31, the latter being operatively mounted on said arm 25. The shaft is also formed with an angular branch 32 and same is constantly disposed in the path of movement of the member 26. It is in this manner that the pin 29 is adapted to be projected to the position shown in Figure 6 and to normally occupy the position shown in Figure 5. A leaf spring 33 is carried by the member 25 and same yieldingly bears against the rear face of the member 26 so as to normally urge the latter in the direction toward the inner face of the dial 11. The member 25 is formed at its outer end with an angular slotted portion or guide flange 34 through which passes the reduced end 35 of the aforesaid member 26, and, as illustrated, said end 35 is provided with a pair of conical studs 36 and 37 which face towards the back of the dial 11. The studs are staggered with respect to each other and they occupy positions relatively to the circle or marking 19 on the dial 11 so as to move along annular paths which are concentric thereto and to be intercepted or obstructed by some of the elements 16 and to coat cam-like therewith during rotation of the hour hand H'. This causes motion to be set up in the rocking shaft 31 and in turn utilized to partly project the pin 29 from the bore 28 in the hour hand arbor 12. In the description to follow, I shall refer to the stud 36 as the "outer stud" and the one 37 the "inner stud." Substantially all of the parts so far referred to mutually serve to constitute my alarm releasing mechanism by means of which the alarm of the clock will be sounded at the predetermined time or times. I have described this mechanism first in the order of the several co-ordinated mechanisms herein employed, feeling that by so doing, one may more readily grasp the operation of said several mechanisms. On reference to Figure 6 of the drawings, it will be noted that the arm 25 has its guide flange 34 formed with a smooth faced foot 38 which is adapted to readily ride against the inner flat face of the aforementioned head or plate 23 during rotation of the hour hand arbor.

On a driven shaft 40 is mounted the aforesaid small pinion 21 as shown in Figure 2. This shaft is adapted to be driven through a

gear train which includes the driving gear 41a as shown in Figures 9 and 10. Except as herein specifically referred to, I of course make no claim to the clock works per se. I shall therefore describe those parts thereof that may be deemed necessary to enable a person skilled in the art to understand and practice the invention. On the center wheel shaft 42 is a cam 43 the same adapted to make one revolution in each hour. This shaft has a gear pinion 44 which meshes with a minute wheel 45 (Figures 9 and 10), the latter meshing with a small gear pinion 46 on the shaft 47 of the minutes indicator 48, the pinions 44 and 46 each having the same number of teeth. The clock frame 49 upon which the shaft 47 is mounted to revolve is provided with a dial 50, the latter positioned in back of a transparent panel 51 mounted in the walls of the casing 10, as shown in Figure 7. The shaft 47 passes through said dial and same has fixed thereto a minute hand 52. This hand is situated behind the panel 51 and same is adapted to coat with the minute markings on the scale of said dial. At this point it should be noted that the scale of the dial 50 is divided into a number of time indicating divisions which exactly coincide with the number of possible time adjustments of the respective elements 16 on the dial 11. When the hand 52 shall have made one complete revolution about its dial 50, the hour hand H' will have traveled one-twelfth its distance about the dial 11. Because of the means herein employed for driving the so-called minutes hand 52, it follows that the action of this hand is operatively synchronized with that of the said hour hand 11. With the matter just preceding in mind and on reference particularly to Figures 9, 10 and 11 of the drawings, it will now be noted that the aforesaid cam 43 on the hour hand arbor 42 is formed with four identically constructed radial lobes 53 which are separated from each other by substantially V-shaped notches 54. Each of these lobes is formed with a smooth peripheral surface 55 whose function and that of each of the notches 54 will be described presently.

Mounted to rock as a unit on the stub shaft 56 of the frame 49 is a lever assembly 57, consisting of arms 58, 67, 68 and 69, all of which are intended to rock as a unit. The arm 58 is formed with a shoulder 59 against which a pin 60 on the long arm 61 of a rocker 62 is adapted to engage when the parts occupy the relative positions shown in Figure 11. This rocker is pivoted to the frame 49 at 63, and at a point below said pivot, said rocker has attached thereto one end of a coil spring 64. The opposite end of this spring is connected with the frame 49 and it thus follows that by the action of said spring the rocker will be urged in the direction of the arrow (a) in Figure 11, the moment the pin 60 is free from said shoulder 59. Said rocker is formed with an arcuate slot 65 in which a stop pin 66 on the frame 49 passes. As previously stated, the lever assembly 57 also includes the arms 67, 68 and 69, the latter having a foot 70 adapted, when the lever assembly tilts under the action of the spring 57a, and to the position shown in Figure 10, to contact with the latching stub 71 on the oscillatory member 72. The member 72 extends from an oscillatory spring tensioned shaft 73, the ends of which are mounted to turn freely in the respective side plates of the frame 49. The spring 73a (Figure 12) of the shaft 73 functions to urge the member 72 in the direction of the

arrow (b) in Figure 9. From said shaft 73 extends a latch arm 74, the free extremity of which is formed with an angular branch 75. Upon reference to Figure 9 of the drawings, it will be noted that when the lever assembly occupies the position therein illustrated, the branch 75 of the arm 74 engages in the notch 76 in the peripheral edge of a disk 77 which latter constitutes a part of a spring actuated hammer operating means 78, (Figure 14) the said disk being carried by a sleeve 77a which is free to rotate on the shaft 79, said sleeve having secured thereto a gear 77b. The gear 77b is adapted to be driven by the spring 80 through the escapement element 87 (Figure 13) co-acting with the escapement wheel 88 of the means 78. The aforementioned latching stub 71 of the oscillating member 72 is adapted to engage in the notch 81 in the end portion 82 of the vibratory hammer arm 83, the hammer 84 of which is correlated to the bell 85 so as to operate thereagainst as would be the ordinary action of like parts in the customary operation of any well known form of alarm clock. It will doubtless suffice to say that the arm 83 is fixed to an oscillatory shaft 86 and that the latter is provided with the escapement element 87 which coacts with the aforementioned escapement wheel 88 of the means 78. From what has been stated, an alarm releasing actuation set up in the shaft 73 will cause the stub 71 to be withdrawn from the notch 81. This will be followed by an immediate release of the branch 75 from the notch 76 in the disk 77 and the member 72 will be then acted upon by peripheral engagement with the disk until the latter shall have made one complete revolution, at which time, the stub 71 will again enter the notch 81 and thus shut off the alarm mechanism.

The arm 67 is adapted to coact with a latch member 89, the same pivoted at 90 to the frame 49, and normally urged to the position shown in Figure 5 by the spring 108. Said member is formed with a hook 91 and a lug 92, the latter spaced apart from the shoulder 93 of the aforementioned hook so that when the member occupies the position shown in Figure 5, the free end of the lug will bear against the offset free end 94 of a leaf spring 95. The spring 95 is secured at 96 to the head 23 and same traverses the open end of the bore of the hour hand arbor where it will be forced to the position shown in Figure 6 against the normal action of the spring 108 when the pin 29 is projected in response to an action set up in the power transferring member 26, such as when one or the other of the cone shaped studs 36 or 37 is acted upon a by a previously set element 16, see Figure 6. The arm 68 is formed with a cam face 97 and on reference to Figure 10, it will be seen that same is adapted to freely enter any one of the spaces 54 between the adjacent lobes 53, at which time the inner face of the arm 67 will come closely against the shoulder 93. When, however, the peripheral face of any one of the lobes is in contact with the edge portion 97 of said arm 68, there will exist a clearance between the shoulder 93 of the latch member 89 and the inner edge portion of said arm, the purpose of which will be explained in the description of the operation of the invention to follow.

The pin 60 on the arm 61 is adapted, when the lever assembly 57 is in the position shown in Figure 10, to engage in the recess 99 in the arm 58 and to ride over the cam face 100 during the return of the arm 62 to the position

shown in Figure 11. On the rear face of the disk 77 is a pin 101 and during rotation of said disk in the direction of the arrow in Figure 10, said pin will engage with an arm 102 of a rock shaft 103, the latter having a lug 104 in the arcuate path of movement of which is disposed a stop 105. This shaft 103 is formed with an actuating lug 106, the spring 64 tending to present the cam edge 107 to said lug. It follows that when the disk 77 moves in a counter-clockwise direction, the pin 101 will coact with the arm 102 and thus urge the lug against the face 107, and, in turn, rock the arm 62 against the action of the spring 64. This causes the pin 60 to bear against the face 100 of the lever 58 and to ride thereover and to finally fall behind the shoulder 59, whereby to sufficiently tilt the lever assembly to raise the foot 70 away from the lug 71, at which time the several co-ordinated mechanisms will have assumed their normal positions.

In Figure 1 of the drawings the element 16 between the hours of twelve and one has been adjusted to a position where its outer end coincides with the circular marking 19 on the outer portion of the dial 11 so that when the hour hand H¹ shall have moved to a position indicative of twelve thirty o'clock, the stud 36 of the member 26 will ride over said element, and in doing so, the member 26 will be rocked against the action of the spring 33. In consequence thereof, motion will be imparted to the shaft 31 to project the pin 29 to the position shown in Figure 6. The pin 29 is thus forced against the leaf spring 95, and the offset end 94 of said spring is brought to bear against the lug 92 of the latching member 89, which, in turn, moves the latter against the normal influence of the spring 108. In operative synchronism with the aforesaid movement of the member 26, the cam wheel 43 will have rotated to the position where its adjacent lobe 53 will have left the edge 98 of the arm 68, allowing the free end of the arm 68 to enter the adjacent space 54 and the entire lever assembly 57 to tilt by virtue of the action of the spring 57a. In so doing, the foot 70 of the long arm 69 will be presented against the latching stub 71 with sufficient force to throw same out of the notch 81 in the hammer arm 83. Concurrently with this actuation the branch 75 of the latching arm 74 will be retracted from the notch 76, (see Figure 10) in the aforementioned disk 77, at which time the alarm spring 80 will function to render the alarm mechanism operative for a sounding of the bell throughout a period of time represented by a complete revolution of the disk 77. When the pin 101 of disk 77 strikes the arm 102, following withdrawal of branch 75 from notch 76, the lug 106 is forced against the cam surface 107, as illustrated in Figure 10, and the arm 61 thereby rocked in a direction to cause the pin 60 to ride over the surface 100 and seat behind the shoulder 59 of arm 58. This forces the entire assembly 57 to move to a position where the foot 70 will be slightly elevated above the stub 71, thus allowing the branch 75 to again enter the notch 76 and latch the hammer arm as soon as the branch 75 re-enters the notch 76 or when the disk 77 makes a complete revolution. Assuming that the pin 101 has acted upon the lug 106 as above stated, the assembly 57 will of course assume the position shown in Figure 11 and the spring 57a now functions to hold the shoulder 59 against the 75

pin 60 of the arm 61, whereby to prevent the latter from moving under the urging action of the spring 64. With the several parts in the positions just described, it is to be understood that the latching member 89 will be entirely released from the arm 67. The hook 91 of the latching member 89 is curved along its edge 109 for a purpose to be explained presently. During normal continuation of the clockwise movement of the cam 43, the peripheral edge of the next successive lobe 53 will gradually wipe against the cam surface of the aforesaid arm 68, gradually tilting the entire lever assembly in a counterclockwise direction, thus causing the shoulder 59 of the arm 58 to leave the pin 60 and allowing the arm 61 to return to the position shown in Figure 9 ready for the next actuation of latching member 89. Simultaneously therewith, the arm 67 rides over the curved edge 109 of the latching member 89 until it shall have again assumed its position shown in Figure 5. It is to be borne in mind that stud 36 having left element 16, the spring 95 has been allowed to retract by withdrawal of pin 29 as will be clearly understood upon reference to Figures 5 and 6. Assuming now that the element 16 between the said hours of twelve and one o'clock has been returned to its unset or innermost position in its dial slot 14, and that all of the remaining elements have been likewise adjusted, it manifestly follows that the cam 43 may freely operate and the peripheral edges of its respective lobes moved across or against the edge 98 of the arm 68 without causing a tripping or releasing of the alarm mechanism. During this action of the said cam the lever assembly 57 will merely oscillate first in one direction as will be compelled by the action of the lobes in their successive engagement against the arm 68 and then in an opposite direction as will be compelled by the action of the spring 57a. The construction of the organization is such that when all of the elements occupy inactive positions or when none of them lie in the path of either of the studs 36, 37, the device may be employed to satisfy the requirements of an ordinary clock. The minutes indicator 48, from the fact that same is driven in operative synchronism with the hour hand, makes one complete revolution to one-twelfth of a revolution of the hour hand H¹. It is to be understood that I am not to be limited in this respect, any more than I care to be confined to the provision of means on the dial 11 for allowing merely four specific actuations to be set up in the alarm mechanism. I have elected the specific arrangement simply because of the one particular use to which the invention may be put.

Next assume that it is desired to cause the alarm to sound first at one thirty o'clock and then at one forty-five o'clock. It is simply necessary to move the element between the hours of one and two to the position illustrated in Figure 1, at which time the division mark 13 on said element will coincide with the annular marking 19 on the dial 11. When the hour hand H¹ shall have reached the position exactly half way between the hours of one and two, and stud 37 will engage the element 16 in like manner as before described and the alarm mechanism will be placed in operation. By the time the next succeeding lobe shall have come into operative action, the stud 36 will have been acted

upon and the alarm mechanism will be tripped at one forty-five o'clock.

When the element 16 on the hour of three is moved to the extreme outer position (Figure 1) the pin 36 will engage therewith and the alarm sounded at three fifteen o'clock.

When the element on the hour of four o'clock is adjusted to the intermediate position (Figure 1) the stud 37 will coat therewith to sound the alarm at four o'clock, and at four fifteen the stud 36 will engage said element and the alarm will be sounded.

I show twenty-four of the elements 16 and each thereof functions in the same manner so that the alarm may sound (1) on any hour; (2) fifteen minutes after the hour; (3) thirty minutes after the hour, and (4) forty-five minutes after the hour. I have elected to do this merely for the reason that the majority of radio programs are for the durations within the range of times herein provided for.

On reference to Figure 9, it will be observed that the free end of arm 68 rests against the face 55 of one of the lobes 53 of cam 43, at which time the edge of arm 67 which confronts the shoulder 93 of latch 89 will be slightly spaced apart therefrom, (see Figure 5). This is to reduce the friction between these parts during movement of the latch to a released position as shown in Figure 6, at which time the free end of arm 68 will drop into the confronting dwell of the cam to effect a sounding of the alarm. It will be appreciated that in order to further relieve the time train of loads, the alarm train is, by virtue of the arrangement herein disclosed, wholly relied upon to return the lever assembly to a position where the foot lever 70 will clear the stud 71 after the alarm is sounded.

In order that one may readily reconcile the terms employed in the claims with like terms employed in the body portion of this description, the term "clock works" shall mean the entire mechanism of the conventional clock herein shown; the term "alarm mechanism" shall include all of the parts ordinarily employed in an alarm clock plus those extra parts which I have herein fully disclosed and specifically referred to; the "hour hand operating means" shall include the intermeshing gear pinions 20 and 21; the "tripping means" shall include the lever assembly 57, the latching member 89 and the rocker 62; the "holding means" for the alarm mechanism shall include the disk 77, arm 63, and the parts 71 and 75; the "setting means" shall include the entire organization of elements 16, and the means for causing periodical actuations of the tripping means and hence the alarm mechanism shall include the spring 95, the pin 29 and the arm 25 and its adjuncts, and it is to be borne in mind that the synchronized operations herein referred to are in part due to the provision of the cam 43 on the hour hand operating shaft of the clock works.

The means for stopping operation of the alarm mechanism at the expiration of a fixed time shall, of course, include the disk 77 and the coating branch 75 of the member 72, the notch 76 of the disk acting cam-like to force said branch out of the notch and allow for such movement of the stub 71 as would be obviously required to free the latter from the notch 81 in the hammer arm 23, and to hold same in this condition until the disk shall have made a complete revolution. When this shall have been accomplished, the alarm mechanism will cease to operate. During

this operation, the pin 101 will engage the arm 73^a and the lug 106 will be forced against the cam edge 107 of the rocker 62, thus moving said rocker and causing the pin 60 thereof to ride over the inclined face 100 and finally come to rest behind the shoulder 59. In doing so, the foot 70 of the arm 69 will be slightly raised away from the stub 71 and to a position above the notch 81, where it cannot prevent the stub 10 from re-entering said notch, the disk 77 having now made one complete revolution.

I claim:

1. A latch releasing organization for the alarm mechanism of a clock, comprising a dial having hour markings; an arbor having a hand coacting with said markings and provided with an axially movable pin; a spring bearing against the pin to urge same in one direction; alarm setting means adjustable from one position to another radially of the dial; pivoted means carried by the arbor and provided with a plurality of relatively staggered studs adapted to successively engage with the setting means when the latter is adjusted to one position, whereby to tilt the pivoted means; and a device cooperable with the pivoted means and with the pin to successively move the latter in response to corresponding movement of said pivoted means, and against the action of said spring.

2. The combination with the dial of a clock, the same having a radial slot; of an alarm setting element slidable in the slot and adapted to be manually moved from one position to another; in the length thereof; and a linear spring attached at one end to the dial and having its opposite end freely passing through the element so that a yielding force will be exerted against the element to hold same in a position of selected adjustment.

3. In an organization of the class described, a clock works including a time train mechanism having an hour hand arbor and a center wheel arbor; an alarm device including an alarm train mechanism; means for holding the alarm train mechanism from operating; a dial having time predetermining elements; movable means on the hour hand arbor positioned to engage the time predetermining elements and to be moved thereby during movement of the hour hand arbor in a clockwise direction; lever means tilttable from one position to another in response to predetermined movement of the center wheel arbor and movement of the hour hand arbor means and disposed to actuate and free the holding means from the alarm train mechanism; and means actuatable through the time train mechanism and the alarm train mechanism for returning the lever means to said one position.

4. In an alarm mechanism, a clock works including a dial having hour markings; an hour hand coacting with said markings; a time train mechanism for the hour hand; an alarm device including an alarm train mechanism; the dial having radial slots, some coinciding with the hour markings and others thereof disposed in intermediate positions with respect to said markings; a time predetermining element in each slot, the same having portions respectively disposed in front and in back of the dial and each of said elements being manually adjustable to a predetermined position in its slot; means for holding the alarm train mechanism

from operating; means controlled through the time train mechanism for releasing the holding means from the alarm train mechanism and including a device movable respectively into and out of engagement with said time predetermining elements during operation of the time train mechanism; and means for effecting re-engagement of the holding means with the alarm train mechanism after a given amount of rotation of said alarm train mechanism.

5. In mechanism of the class described; a dial including an hour hand arbor; an arm fixed to the arbor and disposed at the inner face of the dial and provided with a laterally tilttable member; means for tilting said member in one direction; means on the dial positioned to engage the tilttable member to tilt same in an opposite direction; a pin slidable through the arbor; and an oscillatory shaft on the arm provided with a portion engaging the pin and a portion engaging the tilttable member, whereby to transfer movement in one direction to the pin when the member is tilted in said opposite direction as aforesaid.

6. In an annunciator of the class described, a clock works including a time train mechanism having an hour hand arbor; an alarm device including an alarm train mechanism; means for holding the alarm train mechanism from operating; a dial having a radial slot; a time predetermining element slidably mounted in said slot and adapted to be moved to any one of a plurality of positions in the length of the slot; an arm fixed to the hour hand arbor and provided with tilttable means having a plurality of studs disposed relative to the dial to successively engage and ride over said predetermining element at predetermined times when the element is adjusted to one position in the slot, whereby to successively tilt said tilttable means, and said studs being disposed relative to each other so that when the predetermining element is in another position in the slot, one only of the studs will engage and ride over the element; and means for actuating the holding means to release same from the alarm train mechanism in response to tilting movement of said tilttable means.

7. In time controlled mechanism, a dial having hour markings and an annular series of radial slots, the alternate ones of the slots coinciding with said hour markings and said dial having an indicating mark disposed medially of the ends of said slots; manually adjustable time predetermining elements slidable to respectively different positions of adjustment in said slots relative to said indicating mark as indicative of different time intervals; a time train controlled hour hand arbor, the same having a hand coacting with the aforementioned hour markings; and alarm train releasing means including an element carried by said arbor and formed and disposed relative to the dial for engagement with and adapted to be moved once by any one of said predetermining elements when in one position of adjustment in its slot relative to said indicating mark and to be moved a plurality of times by said element when the latter is adjusted to another position in its slot relative to said indicating mark.
